SCALP COOLING APPARATUS

Zebulon V. Wood and Guilford B. Melton, Gaffney, S. C., assignors of three-fourths to said Zebulon V. Wood and one-fourth to said Guilford B. Melton

Application March 16, 1936, Serial No. 69,159

2 Claims. (Cl. 132—36)

This invention relates to a hair curling apparatus and more especially to means for cooling the scalp while the curling apparatus is in operation. In permanent waving of human hair, it is common practice to apply a number of clamps to selected portions of the hair, each clamp being so constructed and applied as to subject the hair therein to the action of a suitable solution. The heat when applied to the hair, for fixing the waves therein, generates steam from the solution and this steam very often makes its way down through the conventional clamp and pad to the scalp of the person undergoing the treatment resulting in more or less serious scalp burns.

It is, therefore, an object of this invention to provide means for directing a flow of air onto portions of the scalp liable to be burned, for cooling the scalp at this point.

It is a further object of this invention to provide a cooling device for operation in conjunction with a permanent-wave machine comprising a resilient hollow pad having perforations in the lower side thereof adapted to direct a plurality of streams of air onto the scalp to cool the same while the hair is being treated. This pad has an open ended slot which may be closed after the hair has been inserted therein and also has holes adjacent the slot in the pad inclined so as to direct the flow of air inwardly towards the central portion of the pad through which the hair is drawn thereby intensifying the flow of air on the portions of the scalp which are most likely to be injured or burned by the generated steam.

It is a further object of this invention to provide a cooling device for operation in conjunction with a permanent-waving machine comprising a blower, a distributor head for receiving the air from said blower, a plurality of leads from said distributor head for supplying the air to a plurality of pads disposed between the scalp and the heating elements used in curling the hair, said pads having perforations therein, said pads being adapted to rest upon the scalp of the person receiving the permanent wave to direct air upon the person's head to prevent burns from the steam generated by the conventional hair waving device.

Some of the objects of the invention having been stated, other objects will appear as the description proceeds when taken in connection with the accompanying drawings, in which:

Figure 1 is an elevation of a permanent waving machine showing the invention applied thereto;

Figure 2 is a top plan view of the upper portion of Figure 1 taken along the line 2—2;

Figure 3 is a vertical sectional view through one of the outlet valves from the air distributor head shown in the upper left-hand portion of Figure 1;

Figure 4 is an enlarged elevation of the invention shown in conjunction with the conventional hair waving device;

Figure 5 is a vertical sectional view taken along the line 5—5 in Figure 4;

Figure 6 is an isometric view of the perforated pad for directing air on top of the scalp shown in an opened position;

Figure 7 is a sectional view taken along the line 7—7 in Figure 6;

Figure 8 is a bottom plan view of the perforated pad shown in closed position;

Figure 9 is an enlarged cross-sectional view through the pad similar to the lower portion of Figure 5;

Figure 10 is an elevation showing a modified form of the invention shown in conjunction with another type of hair waving device;

Figure 11 is a vertical sectional view taken along line 11—11 in Figure 10;

Figure 12 is an isometric view of the perforated pad shown in an opened position;

Figure 13 is a sectional view taken along the line 13—13 in Figure 12; and

Figure 14 is a bottom plan view of the pad shown in closed position.

Referring more specifically to the drawings, the numeral 10 indicates a suitable base of a permanent-waving machine having mounted thereon standard 11 which projects upwardly and has secured on the upper end thereof a frame 12, said frame having secured thereto an electrical distributor head 13 and an air distributor head 14. The distributor head 13 receives its current through wire 15 which is connected to switch 16. From the other side of switch 16 suitable wires 17 lead to a plug 18 which is inserted into a socket for obtaining the current necessary for operating the machine.

A plurality of conventional cables 20 are suspended from distributor head 13 and have the lower ends thereof connected to the upper portion of heating clamp 22. The cable 20 has wires therein for supplying current to heating elements 23 and 24 which elements are adapted to be clamped around a batch of hair 25 which is wound around a pin 26 and moistened. When the hair is clamped in this position, namely, in the position shown in Figures 4 and 5, the heat generated by the heating elements 23 and 24 fixes

a permanent wave in the hair so clamped and moistened.

Disposed between the batch of hair 25 and the head of the person whose hair is treated, is a conventional clamp 27 and also a cooling pad 28. As heretofore stated, the solution placed upon the hair 26 will become very hot when the heating elements 23 and 24 are placed in operation. As a result, steam is generated, and it frequently occurs that this steam will find its way downwardly through the hair, which is also disposed in the clamp 27, and burn the scalp, especially at a point directly beneath the slots in clamp 27 and pad 28.

15 This has occurred when a heat insulating pad with slot has been used with no cooling means associated therewith.

The applicants have devised the pad 28 for directing air upon the scalp at the proper point so that this steam will be cooled, even if it finds its way downwardly to the scalp. Pad 28 takes the place of the conventional pad. This pad comprises a pair of members 29 and 30 pivoted as at 31a and made of any suitable material such as a phenolic composition or some suitable rigid heat-resisting substance. These members are secured to the upper surface of hollow prongs 31 and 32 respectively, by any suitable means such as having a suitable adhesive disposed between the proximate surfaces of these members, or by having the members 31 and 32 vulcanized to the members 29 and 30 in case the members 31 and 32 are made of rubber. In addition to having the members 29 and 30 glued or vulcanized they are held in their proper position by means of upwardly projecting inturned flange members 33 and 34 which are integral with members 31 and 32.

The members 29 and 31 have a notch cut in one edge thereof, whereas members 30 and 32 have a notch cut in the edge adjacent members 29 and 31, forming a slot 40 through which the hair is passed. In order to facilitate the insertion of the hair within this slot these members have been made so that they are capable of being opened, as shown in Figure 6, and after the hair has been inserted, it can be clamped in the position shown in Figures 5, 8 and 9. In order to insure that the parts of pad 28 will remain closed and in their proper relative position, a projection 41 has been provided which is integral with member 30 and a slot 42 has been provided in the member 29 into which projection 41 tightly fits.

55 It will be noted by referring to Figure 7 that the rivet 31a, about which members 29 and 30 pivot, does not extend entirely through the pad, but since the lower portion of the pad, comprising members 31 and 32, is made of a suitable 60 resilient material such as rubber, when the pad is opened the resilient material will be stretched at the point where the slot 40 ends and therefore allows pivoted movement of the lower portions 31 and 32 about the point 31a. This 65 stretching of the pad will also have a tendency to normally force the parts back to closed position, which is very desirable. The portions 31 and 32 have hollow compartments 44 and 45 into which the air is forced through a suitable opening 46. From the openings 44 and 45 the air is forced downwardly onto the scalp through perforations 47 and 48, the perforations 47 being inclined downwardly and inwardly toward a point disposed directly below slot 40 in the pad and 75 the perforations 48 being disposed in a vertical

position so as to direct the air directly downwardly. The purpose for providing these inclined slots 47 is to concentrate the air at the point on the scalp directly below the slot 40 where the scalp is more likely to be burned from steam generated by the hair curling apparatus disposed thereabove. Connected to the pad 28 as at 46, is a suitable tube 50 which leads upwardly and is secured to a valve 51, said valve 51 being secured in air distributor 14. This valve may be 10 operated manually by turning the valve cock 52. (Figure 3.) While only one hair-curling device is shown in the drawings associated with a cooling pad it is evident that there will be a cooling pad for each curling device, which in most instances range, in number, from twenty upwardly. 15

In order to supply the air to the distributor 14 a pipe 55 has one end thereof secured thereto, which pipe has its other end secured to fan 56 which is driven by a suitable motor 57. The motor 57 is preferably a variable speed type which may be regulated to determine the amount of air which is supplied to the distributor 14. The distributor 14 also has a plug 59 therein to which a hose may be attached for cooling the scalp by 25 an apparatus which is operated independently of the hair curling apparatus, or for performing other functions about the machine. The conventional hair curling device and the applicants' cooling device is suspended by a cord 60 which 30 leads upwardly to the member 12 and rearwardly of the machine through a suitable eyelet in bar 61, and thence downwardly, where it is secured to the upper end of a suitable counterweight 62. This provides means for holding the cooling and 35 curling devices in an elevated position when not in use.

The thickness of the pad and associated parts as shown in Figures 4 and 5 is exaggerated for sake of clearness, as it is evident that these pads 40 in practice are much thinner than shown.

Figures 10 to 14 inclusive show a slightly modified form of the invention associated with another type of permanent wave device. This is a vertical type of hair curling apparatus which 45 comprises a hollow member 65 having a conventional heating element 66, to which current is supplied by means of suitable wires 67. A pin 68 has a bunch of hair 69 wound around the lower portion thereof and when the hair is moistened 50 it is inserted within the hollow member 65 in the position shown in Figure 11 where the heating element will supply the heat for fixing the wave in the hair. In this form it is evident that the steam generated as a result of the liquid applied 55 to the batch of hair 69 while being heated by heating element 66, will cause the scalp to be burned especially directly below the heating element when the conventional pad is used.

The conventional pad which fits directly upon 60 the scalp has been dispensed with and a perforated cooling pad 70 has been inserted in lieu thereof. This pad comprises a pair of rigid members 71 and 72 pivoted as at 73 to each other. The members 71 and 72 are made of any suitable material as phenolic condensate. The lower surface of members 71 and 72 (Figures 10, 11 and 12) are secured to the upper portion of hollow prongs 75 and 76 by any suitable means such as vulcanizing or applying a suitable adhesive between the 70 proximate surfaces thereof. The members 75 and 76 are made of any suitable elastic material such as rubber and have cavities 77 and 78 respectively therein into which a current of air is introduced through inlet 79. When air enters these 7

cavities it is directed downwardly upon the scalp through orifices 80 and 81, the orifices 81 being inclined inwardly towards the central portion of the pad 70 whereas, the orifices 80 are so positioned as to direct the air directly downwardly parallel to the longitudinal axis of the pad. This pad is similar in construction to the pad previously described and it will be noted that the lower portion of the pad is not slit to the left in Figure 13 to the pivot point 73, but since the lower portion is resilient, the material near the pivot point 73 will stretch and allow the portions comprising members 71, 72, 75 and 76 to be opened in the manner shown in Figure 12 about pivot 73. These members also have their proximate surfaces in the central portion thereof cut out to form a hole 83 through which the hair is drawn before it is wound around the pin 68 and inserted into the device 65. In order to insure that the free ends of members 71, 72, 75 and 76 will remain in the proper relative position, a projection 84 has been provided on the member 72 which is adapted to fit in a suitable cavity 85 cut in member 71 when the device is in closed position as shown in Figure 14.

It is therefore, seen that this device may be inserted in lieu of the pads and applied to the head of a person with ease since the members 71, 72, 76 and 75 will pivot about the pivot point 73. The air is supplied to the members 75 and 76 by means of the tube 50 which is inserted over the stem having the inlet 79 therein. Also, if desired a suitable shield 87 may be provided over the lower end of tube 50 to protect the tubing from the heat generated during the curling operation.

In the drawings and specification there has been set forth a preferred embodiment of the invention, and although specific terms are employed, they are used in a generic and descriptive sense only, and not for purposes of limita-

tion, the scope of the invention being set forth in the appended claims.

We claim:

1. A head protecting shield for use in protecting the scalp in the art of permanent hair waving, said shield comprising a hollow resilient pad having an open ended slot therein which is adapted to encircle a bunch of hair adjacent the scalp, the side of the pad disposed adjacent the scalp having a plurality of perforations adjacent the perimeter of said slot with the longitudinal axes of said perforations forming an acute angle with the longitudinal axis of said slot, and means for forcing air under pressure through said perforations to cool the scalp, the side of the pad remote from the scalp having secured thereto a pair of rigid members pivoted to each other at the closed end of the pad and being separable from each other at the open end of said pad.

2. A head protecting shield for use in protecting the scalp in the art of permanent hair waving, said shield comprising a hollow resilient pad having an open ended slot therein which is adapted to encircle a bunch of hair adjacent the scalp, the side of the pad disposed adjacent the scalp having a plurality of perforations adjacent the perimeter of said slot with the longitudinal axes of said perforations forming an acute angle with the longitudinal axis of said slot, the side of said pad adjacent the scalp having a plurality of other perforations whose longitudinal axes are parallel to the longitudinal axis of said slot and means for forcing air under pressure through said perforations to cool the scalp, the side of the pad remote from the scalp having secured thereto a pair of rigid members pivoted to each other at the closed end of the pad and being separable from each other at the open end of said pad.

ZEBULON V. WOOD.
